[57] CLAIM

The ornamental design for a television receiver, as shown and described.

DESCRIPTION

FIG. 1 is a front, top and right side perspective view of a television receiver showing our new design;

FIG. 2 is a rear, bottom and left side perspective view thereof; and

FIG. 3 is a view like FIG. 1, with the pivotable cover lowered and the screen retracted.

FIG. 1

FIG. 2

FIG. 3
